CLAIM

The ornamental design for a hold down device for a beach blanket or similar article, as shown and described.

DESCRIPTION

FIG. 1 is a top front perspective view of a hold down device for a beach blanket or similar article showing my new design;

FIG. 2 is a side elevational view taken from the front of FIG. 1;

FIG. 3 is a rear elevational view thereof;

FIG. 4 is a side view thereof;

FIG. 5 is a top plan view thereof;

FIG. 6 is a bottom plan view thereof.

FIG. 1.

FIG. 2.

FIG. 3.

FIG. 4.

FIG. 5.

FIG. 6.
